UNITED STATES PATENT OFFICE.

JOHN BLAND, OF CHICAGO, ILLINOIS.

GRINDER.

Application filed December 10, 1924. Serial No. 754,892.

This invention relates to a machine and process of grinding. One object of the invention is to provide a machine which will grind and break up mica and other similar laminated material. Another object is to provide a means for mechanically bending mica or other laminated material to break the same, into as thin sections as possible. Other objects will appear from time to time throughout the specification and claims.

My invention is illustrated more or less diagrammatically in the accompanying drawings, wherein:

Figure 1 is a plan view with parts in section;

Figure 2 is a side elevation;

Figure 3 is a transverse vertical cross section on line 3—3 of Figure 2 on an enlarged scale;

Figure 4 is a longitudinal vertical cross section on line 4—4 of Figure 3 on a further enlarged scale.

Like parts are designated by like characters throughout.

A is a foundation which preferably has two or more raised cross members A¹ A¹.

Resting upon this foundation are the grinding members proper. In the form here shown the grinding members consist of six superimposed generally horizontal perforated and slotted plates. The bottom plate B is the thinnest of all of the plates and rests upon the members A¹ and is perforated, and through the perforations it engages the vertical posts B¹. These posts are braced by lateral bracing members B² which are secured to the foundation A¹ by means of bolts B³. The plate B is provided in its upper face with a plurality of grooves or slots C.

These slots extend approximately across the plates but are not parallel to the ends of the plates, that is they do not run at right angles to the longitudinal axis of the plate. The plate is further provided with perforations C¹. These perforations are wider than the slots but lie in them so that in effect the slot runs from perforation to perforation across the face of the plate.

D are rollers mounted upon the vertical posts B¹. One of the rollers as shown in Figure 3 rests immediately upon the upper surface of the plate B.

E is a second plate. It lies upon and moves over the plate B. It is provided in its upper face with a series of grooves E¹ simi-

lar to the grooves C. In its lower surface it is provided with a series of grooves E² similar to the grooves E¹. The grooves E² are, however, not parallel to the grooves C in the plate B, and thus the plates do not lock and the grooves or slots do not engage as the plates move with relation to each other. The plate E has a plurality of perforations E³ which communicate with the slots E¹ E². The outer edges of the plate E engage the lower rollers D.

F is a third plate resting upon the plate E and provided in its upper surface with slots F¹ and in its lower surface with slots F², and having perforations F³. It is perforated at its edges and engages and is secured by the vertical members B⁴.

G is a fourth plate resting upon the upper surface of the plate F and having grooves G¹ in its upper surface, and a series of grooves G² in its lower surface and perforations G³. It rests upon the plate F in the same manner as each of the other plates rests upon the one below it, and the grooves in its lower face are not parallel with the grooves in the upper face of the plate F so that the two do not lock.

H is a fifth plate resting on the plate G. It has grooves H¹ in the upper face, H² in its lower face and perforations H³.

I is a sixth plate having grooves I¹, grooves I² and perforations I³.

The plates increase in thickness from bottom upward, each successive plate being somewhat thicker than the one below it, although this is not an absolutely essential feature and for some purposes might be departed from. The perforations through the plates also preferably decrease progressively in size from top to bottom, the largest perforations being in the top plate and the smallest in the bottom plate, and correspondingly therefore the depth of the groove is preferably increased from the bottom up so that the widest and deepest grooves are in the top plate and the narrowest and shallowest grooves being in the bottom plate.

J are braces which rest upon the top and uppermost plate in a position not parallel to the grooves in the top of the upper plate and serving in combination with the grooves in the upper plate initially to break and grind material fed to the machine.

Each of the plates E, G and I engages at its outer edge the rollers D. K are longi-

tudinal braces to which the cross braces J are secured. Each of the plates E, G and I is secured to a hook L which is jointed to a piston member L¹ carrying a piston head L².
 5 This latter is mounted within a cylinder M which carries on its one end a piston rod M¹ which in turn carries a piston head M². This piston head M² is mounted within a steam chest or cylinder M³ carried on a foundation
 10 A. M⁴ M⁵ are steam or other fluid connections by means of which pressure may be alternately applied to one side or the other of the piston M². N is a helical spring about the member L within the cylinder M and N¹
 15 is a similar spring located within the cylinder M bearing at one end against the piston head L² and at the other against the closed end of the cylinder M. The spring connection permits a certain amount of
 20 yielding as the parts are moved and thus avoid undue strain and breakages.

Although I have shown an operative device, still it will be obvious that many changes will be made in size, shape and arrangement of parts without departing materially from the spirit of my invention; and I wish therefore, that my showing be taken as in a sense diagrammatic.

While I have shown the plates as being of decreasing thickness from top downward, the thickest being at the top and the thinnest at the bottom; it is not an essential feature of the invention and the invention is not limited to this construction. The plates
 30 might be all of one thickness or the moving plates might be of one thickness and the stationary plates of another thickness, or the thickness of the plates might be graduated differently.

40 The use and operation of my invention are as follows:

When material is to be ground the alternate plates are moved with relation to each other. In the form here shown the bottom plate is stationary. Counting from the bottom the second, fourth and sixth plates are moving. These plates are fastened together and are moved in and out. The first, third and fifth plates remain stationary. Thus
 45 the grooves and perforations in alternate plates pass and repass each other as the plates are reciprocated in and out.

50 Material to be crushed is placed upon the upper plate and falls between the bars. Then as the plates are moved the grooves in the upper plate move with relation to the fixed plates. Some of the material is caught in these grooves and is forced against the bars and is thus crushed and broken and some of it then passes down through the perforations in the upper plate to the space between the upper and lower plate and lies partly in the grooves in the bottom of the
 55 lower plate and partly in the grooves in the top of the upper plate. Relative movement
 60

of these two plates repeats the action, that is to say, a piece of material will be caught on one edge in the groove of the lower plate and on the other edge in the groove of the upper plate. As the two move toward each other the material will be crushed and broken and will be further reduced in size and will pass downward through the perforations in the second plate, and so on from plate to plate, each time broken and reduced in size and each time after being once broken passing through the perforations to a lower plate, and so finally until it passes to the bottom plate and through it into a receiving device, having been reduced in size.

65 A particular feature of importance of this invention is that it is designed to operate upon laminated material, and particularly upon mica. This is a material which it is very difficult to crush and which must be bent to reduce it to the thinnest possible size. It can with difficulty be crushed, but it can be cut and sheared, but when so treated, if nothing further is done, it does not become reduced to its finest possible size. In order to reduce the pieces of mica to their thinnest possible dimension it is necessary to bend them. The laminations are thus separated and the mica is reduced to a very much smaller size than is possible where bending does not take place. Therefore one of the most important features of this invention is that the mica is bent and bent again and again. Initially, of course, at the top of the machine comparatively large sheets of mica are thrown in, one edge of the sheet
 70 catching in the perforations in the upper plate, its other edge striking against one of the upper bars, and then as the plate continues to move the pieces of mica will be bent and the laminations to some extent separated.

75 All of the mica on the top of the machine is treated this way until it has been reduced after successive bendings to a sufficient size to pass through the perforations in the upper plate, and then it comes downward and the same successive bendings take place. In this way one edge of the piece will catch in a groove of the lower plate and another edge of the same piece will catch in the grooves of the upper plate, and as the two move together the piece of mica will be bent. This continued bending and re-bending and consequent separation of the laminations of material takes place, and of course there is associated with this bending action a certain amount of grinding and crushing and breaking so that the pieces of mica are not only reduced in thickness but are reduced in other dimensions. Thus the mica is split by bending and to some extent sheared and cut and is broken and consequently reduced to an extremely small size.

80 Another feature of importance is the lubrication of the machine. As particles of

mica work downward through the machine they come to be evenly distributed between all of the contacting surfaces of the adjacent plates, and the plates therefore are not moved in contact with each other but they are separated from each other by the mica, which lies between their contacting faces and they are lubricated by this mica. Thus the material as it is crushed bent and broken furnished its own lubricant for the machine and prevents undue wear and friction of the parts.

I claim:

1. In a grinder, a plurality of plates one resting on the other, said plates having grooves in their contacting faces, there being perforations through the plates, and means for reciprocating one of them.

2. In a grinder, a plurality of plates, one resting upon the other, said plates having grooves in their contacting faces, the grooves running generally diagonally across the plates, the grooves in one plate being at an angle to the grooves in the contacting face of the other plate, there being perforations through the plates, and means for reciprocating one of them.

3. In a grinder, a plurality of plates, one resting upon the other, said plates having grooves in their contacting faces, the grooves running generally diagonally across the plates, the grooves in one plate being at an angle to the grooves in the contacting face of the other plate, there being perforations through the plates, and means for reciprocating alternate plates in unison.

4. In a grinder, a plurality of plates one resting on the other, said plates having grooves in their contacting faces, there being perforations through the plates, and means for reciprocating alternate plates in unison.

5. In a grinder, a plurality of plates, one resting upon the other, said plates having grooves in their contacting faces, the grooves running generally diagonally across the plates, the contacting sets of grooves meeting at an angle to each other, there being perforations through the plates, and means for reciprocating one of them.

50 6. In a grinder, a plurality of plates, one resting upon the other, said plates having grooves in their contacting faces, the grooves running generally diagonally across the plates, the contacting sets of grooves meeting at an angle to each other, there being perforations through the plates, and means for reciprocating alternate plates in unison.

7. In a grinder, a plurality of plates, one resting upon the other, said plates having grooves in their contacting faces, the grooves running generally diagonally across the plates, the grooves in one plate being at an angle to the grooves in the contacting face of the other plate, there being perforations through the plates, and means for reciprocating

cating alternate plates in unison, the plates progressively decreasing in thickness from top to bottom, the thickest plate being at the top and the thinnest plate being at the bottom.

70 8. In a grinder, a plurality of plates, one resting upon the other, said plates having grooves in their contacting faces, the grooves running generally diagonally across the plates, the contacting sets of grooves meeting at an angle to each other, there being perforations through the plates, and means for reciprocating one of them, the plates progressively decreasing in thickness from top to bottom, the thickest plate being at the 80 top and the thinnest plate being at the bottom.

85 9. In a grinder, a plurality of plates, one resting upon the other, said plates having grooves in their contacting faces, the grooves running generally diagonally across the plates, the contacting sets of grooves meeting at an angle to each other, there being perforations through the plates, and means for reciprocating alternate plates in unison, the plates progressively decreasing in thickness from top to bottom, the thickest plate being at the 90 top and the thinnest plate being at the bottom.

95 10. In a grinder, a plurality of plates, one resting upon the other, said plates having grooves in their contacting faces, the grooves running generally diagonally across the plates, the grooves in one plate being at an angle to the grooves in the contacting face of the other plate, there being perforations through the plates, and means for reciprocating alternate plates in unison, the grooves in the lower plates being smaller than the grooves in the upper plates, the smallest grooves being in the bottom plate and the largest grooves being in the top plate.

100 11. In a grinder, a plurality of plates, one resting upon the other, said plates having grooves in their contacting faces, the grooves running generally diagonally across the plates, the contacting sets of grooves meeting at an angle to each other, there being perforations through the plates, and means for reciprocating one of them, the grooves in the lower plates being smaller than the grooves in the upper plates, the smallest grooves being in the bottom plate and the largest grooves being in the top plate.

115 12. In a grinder, a plurality of plates, one resting upon the other, said plates having grooves in their contacting faces, the grooves running generally diagonally across the plates, the contacting sets of grooves meeting at an angle to each other, there being perforations through the plates, and means for reciprocating alternate plates in unison, the grooves in the lower plates being smaller than the grooves in the upper plates, the smallest grooves being in the bottom plate

and the largest grooves being in the top plate.

13. In a grinder, a plurality of plates, one resting upon the other, said plates having 5 grooves in their contacting faces, the grooves running generally diagonally across the plates, the grooves in one plate being at an angle to the grooves in the contacting face of the other plate, there being perforations 10 through the plates, and means for reciprocating alternate plates in unison, the perforations decreasing in size downwardly, the largest perforations being in the top plate, and the smallest perforations being in the 15 bottom plate.

14. In a grinder, a plurality of plates, one resting upon the other, said plates having grooves in their contacting faces, the grooves running generally diagonally across the 20 plates, the contacting sets of grooves meeting at an angle to each other, there being perforations through the plates, and means for reciprocating one of them, the perforations decreasing in size downwardly, the 25 large perforations being in the top plate and the smallest perforations being in the bottom plate.

15. In a grinder, a plurality of plates, one resting upon the other, said plates having 30 grooves in their contacting faces, the grooves running generally diagonally across the plates, the contacting sets of grooves meeting at an angle to each other, there being perforations through the plates, and means 35 for reciprocating alternate plates in unison, the perforations decreasing in size downwardly, the largest perforations being in the top plate, and the smallest perforations being in the bottom plate.

16. In a grinding apparatus, a plurality of superimposed plates, each plate having on its contacting surfaces grooves and perforations passing through the plates in line 45 with the grooves, the thickness of the plates, the size of the grooves and the size of the perforations being graduated, the smallest of each at the bottom, the largest of each at the top, and means for reciprocating in unison alternate plates.

17. In a grinding apparatus, a plurality of superimposed plates, each plate having on its contacting surfaces grooves and perforations passing through the plates in line 55 with the grooves, and of greater width, the thickness of the plates, the size of the grooves and the size of the perforations being graduated, the smallest of each at the bottom, the largest of each at the top, and means for reciprocating in unison alternate plates.

18. In a grinding apparatus, a plurality of superimposed generally horizontal metal plates, each plate having on its contacting 60 surfaces grooves and perforations passing through the plates in line with the grooves

and of greater width, the thickness of the plates, the size of the grooves and the size of the perforations being graduated, the smallest of each at the bottom, the largest of each at the top, and means for reciprocating 70 in unison alternate plates.

19. In a grinder, a plurality of generally horizontal plates of metal, each of said plates having grooves in its upper and lower surface, the grooves running generally diagonally across the plates, there being perforations through the plates in line with the grooves, of greater width than the grooves, the plates decreasing in size from top to bottom of the grinder, the grooves decreasing in width from top to bottom, and the size of the perforations decreasing from top to bottom, and means for reciprocating alternate plates in unison, and bars diagonally across and above the upper plate, the bars resting on the top plate, and each plate resting upon the one beneath it.

20. In a grinder, a plurality of plates, of greater width than the grooves, one resting 90 on the other, said plates having grooves in their contacting faces, there being perforations through the plates, and means for reciprocating one of them.

21. In a grinder adapted to reduce laminated material means for engaging the material to bend it to separate the laminations, said means including a plurality of plates, one resting on the other, said plates having material engaging grooves in their contacting faces, there being perforations through the plates through which the material acted upon may fall to successive plates, and means for reciprocating alternate plates in unison.

22. In a grinder adapted to reduce laminated material means for successively engaging the material to bend it to separate the laminations, said means including a plurality of plates, one resting on the other, said plates having material engaging grooves in their contacting faces, there being perforations through the plates through which the material acted upon may fall to successive plates and means for reciprocating alternate plates in unison.

23. In a grinder adapted to reduce laminated material means for successively engaging the material to bend it to separate the laminations, said means including a plurality of plates, one resting on the other, said plates having material engaging grooves in their contacting faces, there being perforations through the plates through which the material acted upon may fall to successive plates and means for reciprocating alternate plates in unison, the plates progressively decreasing in size downwardly, the largest plate being at the top and the smallest one at the bottom.

24. In a grinder adapted to reduce lami-

- nated material means for successively engaging the material to bend it to separate the laminations, said means including a plurality of plates, one resting on the other, 5 said plates having material engaging grooves in their contacting faces, there being perforations through the plates through which the material acted upon may fall to successive plates and means for reciprocating alternate plates in unison, the thickness of the plates, size of the grooves and perforations progressively decreasing, the smallest of each being at the bottom and the largest of each at the top.
- 10 25. The process of breaking up laminated material which consists in engaging edges of a piece of such material and forcing the two towards each other to cause bending and splitting.
- 20 26. The process of breaking up laminated material which consists in repeatedly engaging edges of a piece of such material and forcing the two towards each other to cause bending and splitting.
- 25 27. The process of breaking up laminated material which consists in engaging edges of a piece of such material and forcing the two towards each other to cause bending and splitting and passing such partially separated pieces downward through a plurality 30 of

of bending and splitting zones and repeating the bending operation in such zones by engaging the edges of a piece of such material and forcing the two towards each other.

28. The process of breaking up laminated material which consists in repeatedly engaging edges of a piece of such material and forcing the two towards each other to cause bending and splitting and passing such partially separated pieces downward through a plurality 35 of bending and splitting zones and repeating the bending operation in such zones by engaging the edges of a piece of such material and forcing the two towards each other.

29. In a grinder adapted to reduce laminated material means for engaging edges of said material and for moving such edges together to bend and to separate the laminations.

30. In a grinder adapted to reduce laminated material means for successively engaging edges of said material and for moving such edges together to bend and to separate the laminations.

Signed at Chicago county of Cook and State of Illinois, this 19th day of November 1924.

JOHN BLAND.
